UNITED STATES PATENT OFFICE.

LOTHAR R. ZIFFERER, OF LANCASTER, PENNSYLVANIA.

RECEPTACLE.

1,352,495.

Specification of Letters Patent. Patented Sept. 14, 1920.

Application filed April 16, 1918, Serial No. 228,823. Renewed January 26, 1920. Serial No. 354,250.

To all whom it may concern:

Be it known that I, LOTHAR R. ZIFFERER, a citizen of the United States, residing at Lancaster, in the county of Lancaster and 5 State of Pennsylvania, have invented certain new and useful Improvements in Receptacles, of which the following is a specification.

This invention relates to an improved receptacle for garbage, refuse, waste, etc., of the general kind shown and described in my Patent No. 1,247,058, issued November 20, 1917.

Primarily my invention is concerned with 15 means by which the cover of the receptacle may be raised and lowered. The cover operating means which will be presently described is formed separately and distinctly from the receptacle itself which may be 20 loosely positioned within the frame carrying the cover operating means. When operatively placed in position, the receptacle cannot be removed from the frame without first raising the cover. As the only way in which 25 the cover may be raised is by actuation of the cover operating means, it will ordinarily be impossible for animals to gain access to the interior of the receptacle. The means by which my invention attains the general objects just stated are clearly set forth in the 30 accompanying specification wherein reference is made to the drawings in which—

Figure 1 exhibits a side elevation of a preferred embodiment of my invention, the 35 dotted lines representing the parts as moved to bring the cover to raised position;

Fig. 2 is a rear elevation thereof; and

Fig. 3 is a plan view of the frame, the receptacle and cover being removed to better 40 exhibit the construction and arrangement of the parts.

The mechanism constituting the present invention may be conveniently formed of some such material as malleable iron arranged to provide a substantial and serviceable structure. As best shown in Fig. 1, this structure includes a circular base 4 mounted upon suitable legs 5, intersecting braces 6 being extended across the base below its 45 upper edge. By this construction a circular frame is provided in which a cylindrical receptacle 7 may be placed and held in operative position.

Depending from the intersection of the 50 cross braces 6 are one or more lugs 8, carry-

ing a pin 9 adapted to afford a pivotal mounting for a treadle 10 whose forward end is formed to provide a pedal 11. A spring 12 may be employed, if desired, to hold the treadle in such relation to the frame 60 that its forward end is normally raised, as best shown in Fig. 1. A stop member 13 carried on the treadle and arranged to engage with the under side of one of the braces 6 serves to limit the swinging movement of the treadle in one direction.

Secured upon the rear side of the base is an upright member 14 formed with webs 15 suitably curved in conformity with the periphery of the base 4 and secured thereto 70 by rivets 16 or any other suitable connection. Means for correctly positioning the upright member upon the base are provided in the shape of ears 17 which project inwardly from the member to lie upon the upper edge 75 of the base 4. The lower end of the upright member is formed to present companion lugs 18 which depend below the base 4, a pin 19 being extended between these lugs to afford a pivotal mounting for a bell crank 20. Preferably this bell crank is formed as shown in Fig. 2, with companion sides between which is extended a pin 21 at the inner end and a pin 22 at the other end. The pin 21 lies in proximate relation to the rear end 80 of the treadle 10 and is adapted to execute a sliding movement within a slot 23 formed therein (see Fig. 1). By means of the construction illustrated, the treadle may actuate the bell crank 20 in such a way as to swing 85 it into the position indicated by the dotted lines in Fig. 1.

Pivots connected with the pin 22 at the upper end of the bell crank is a link 24, whose upper end has a pivotal connection as 90 at 25 with a lever 26 which is pivoted to the extremity of the upright member 14 as at 27. As best appears in Fig. 2, the upper end of the upright is forked to provide a substantial mounting for the lever 26, the 100 end of the lever wherein the pin 25 is situated being disposed rearwardly of the upright, and the forward end 28 of the lever 26 being extended over the base of the frame to a point where it may engage with the receptacle cover 29. A convenient means for detachably connecting the lever 26 to the cover is suggested, comprising a button 30 secured to the cover and arranged to present its shank within a slot 31 formed in the 110

lever 26, the button overlying the upper face of the lever when swiveled into transverse position (see Fig. 2).

The operation of the present device should be entirely clear from the preceding description when read in connection with the several figures of the drawings. It is of special importance to note that normally the upper end of the bell crank 20 is in substantial alinement with the link 24—that is, the pin 22 lies in dead center relation between the pivotal points 19 and 25, so as to prevent raising of the cover except by operating the treadle. When, however, pressure is applied to the pedal of the treadle, the bell crank 20 will be swung upon its pivot 19 until the parts are brought into the position indicated by the dotted lines in Fig. 1. When the cover is thus raised, the receptacle 7 may be removed from the frame by means of the bail 32, or in any other way that is preferred. To replace the receptacle in operative position it is necessary merely that the cover should be raised whereupon the receptacle may be fitted back into the base of the frame, its rotative position relative thereto being a matter of no importance. After the cover has been allowed to drop back in place (this action being facilitated by the pressure of the spring 12), the device as a whole may be moved about by seizing the bail, or in any other convenient manner, it being obvious that when so handled the cover will remain seated to prevent the receptacle from leaving the frame.

In the construction illustrated, I have shown the parts to be formed in a substantial manner such as would be preferred if the device were made of cast metal. Such details, however, are not essential to the invention, which relates primarily to the cover operating means which is formed independently of the receptacle, and which is incapable of operation except by applying pressure to the treadle in the manner intended.

I claim:

1. A frame providing a mounting for a receptacle and carrying means for raising the receptacle cover including a treadle, a lever pivoted to the frame and having connection with the receptacle cover, a bell crank pivoted to the frame and having connection with the treadle, and a link pivotally connected to the lever and to the bell crank, the point of pivotal connection between the link and bell crank normally remaining in dead

center relation between the pivotal point of the opposite end of the link and the pivotal center of the bell crank, whereby motion may be transmitted only from the direction of the treadle, substantially as described. 60

2. A frame providing a mounting for a receptacle and carrying means for raising the receptacle cover including a treadle, a lever pivoted to the frame and having connection with the receptacle cover, a bell crank pivoted to the frame and having connection with the treadle, and a link pivotally connected to the lever and to the bell crank, three of the pivotal centers being normally arranged in substantial alinement whereby motion may be transmitted only from the direction of the treadle, substantially as described. 65 70

3. A frame providing a mounting for a receptacle and carrying means for raising the receptacle cover including a treadle, and interconnecting elements adapted for simultaneous operation when the treadle is actuated, one of said elements having connection with the receptacle cover and adapted to raise the same when the treadle is actuated, the several elements being normally in such relation as to prevent their transmitting motion except from the direction of the treadle, substantially as described. 75 80

4. A frame providing a mounting for a receptacle and carrying means for raising the receptacle cover including a treadle pivoted to the frame, a lever pivoted to the frame and connected with the receptacle cover, and interconnected elements between the treadle and lever adapted for simultaneous operation to transmit motion from the treadle to the cover, the normal position of the elements relative to each other being such as to prevent their operation except when motion is first imparted by the treadle, substantially as described. 95

5. A frame providing a mounting for a receptacle and carrying means for raising the receptacle cover including a treadle, and elements interconnecting the treadle and cover adapted for simultaneous operation, the said elements being so related as to resist in and of themselves any operative movement except when the treadle is first actuated, substantially as described. 100 105

LOTHAR R. ZIFFERER.
